United States Patent Office.

HORACE T. LOVE, OF VERMILLION TOWNSHIP, KANSAS.

Letters Patent No. 60,756, dated January 1, 1867.

IMPROVED FASTENING FOR RAILROAD RAILS.

The Schedule referred to in these Letters Patent and making part of the same.

TO ALL WHOM IT MAY CONCERN:

Be it known that I, HORACE T. LOVE, of Vermillion Township, in Marshall county, in the State of Kansas, have invented a new and improved Mode of Fastening Down the Iron Rails and the Chairs of Rails of Railways, and for uses analogous; and I do hereby declare that the following is a full and exact description thereof, reference being had to the accompanying drawings, and to the letters of reference marked thereon, making a part of this specification.

To fasten down rails and chairs of rails on railroads, the fastener, in order to fulfill its purpose properly, must have the power to bring the rail down tight upon its wooden substructure, and then, without relaxation, to hold it there, as against all ordinary strain, and must also be able to let go its hold, when desirable, without injury either to itself or to the wooden substructure into which it is made to penetrate. It must, therefore, be, in turn, both a fastener and a loosener, as may be desired. If a common spike, four or five inches long and a half an inch thick, be driven into a railroad tie, its hooked head, when driven home, will bring the rail down on to the tie; but the strain of the first heavy train, by its weight, velocity, and vibration, will loosen the spike and break its hold on the wood; moisture will enter the hole, the spike will rust, the rails, jostled about, will move up and down, to and fro, by the passing trains; the wheels, by continual impinging, battering up the ends of the rails, and the rails in turn sloughing out the face of the wheels, soon render them eccentric and unfit for use; and though an army of operatives is employed to keep roads in repair at countless expense, yet, in spite of all precautions, vigilance, and activity, the rails are forever loose, and every now and then a train leaps from the track and plunges headlong to a heap of ruins, to the frightful destruction of human life and loss of untold treasure; and yet this same hook-headed spike to-day is the usual iron-rail fastener of the railways of the whole world. Various have been the modes devised to remedy this universal defect in rail fasteners, but hitherto all have been abortive. The bearded and the self-clinching spike have both been tried; but they, having "holding power" sufficient, do so lacerate and split up the ties, when they have to be withdrawn to liberate the rails for repair and other purposes, they have come to be regarded as a failure and condemned accordingly. More recently the "screw-spike," so called, has been tried, consisting of a "double-hooked" or "T" head; and this, while having desirable power to hold against any ordinary strain and to liberate the rails at pleasure, fails in the vital point that it contains no mechanical principle whereby to secure the screwing down tight of the rail upon the tie, thus leaving the very evil untouched which first of all should have been removed. To illustrate, the single thread of this screw as made is of about one-quarter of an inch gauge, and will of course sink the screw that distance in the wood at each revolution of the screw, and half that distance at every half revolution. Now, as this screw-spike must be turned half way round to bring its hooked head into position to get a bearing on the flange of the rail, it follows that whenever the distance between hook and flange in screwing it down is less than half the gauge of the screw (less than one-eighth of an inch in this case) the hook will of necessity, in making its half revolution, impinge against the edge of the flange, instead of getting a bearing upon the upper surface of the flange, and the consequence is that play to the distance of one-eighth of an inch or less is left between the hooked head and flange. The rail is left loose; and this evil, when rails come to be relaid upon old ties, is greatly increased. In this case the spike driven into a new place, and near the end, and the tie no longer green, is sure to split it. The old hole and new crack, being exposed to rain and snow, rot speedily ensues, and the consequence is that the tie itself becomes useless and must be immediately replaced by new, or the road must be abandoned. To these imperfect and faulty modes of fastening down the rails of railways, whereby they are always found loose, I have invented a complete remedy. My invention consists—

First. In an auger or auger bit, as shown Figure 1 or Figure 2, capable of making a hole having two diameters, the larger whereof is at the mouth or top of the hole.

Second. In a key, shown in Figure 3, to lock this bit into the machine, whereby it is operated, and to gauge it so as to bore the desirable depth of hole, particularly the depth of that part thereof having the larger diameter. The counterpart to which key is shown in the catch *n'* in shank of the bit in figs. 1 and 2.

Third. In a screw-fastener, shown in Figure 4, having the under part of its head in form cam-like, whose inclination is inversely to the inclination of the thread of the screw and of no less gauge than that of the

thread, the side of which head is truncated by a line passing through *a b c d* in fig. 4, tangent to the shank of the screw. Figure 5 shows truncated heads of screw-fasteners, *a b c d e l m n o p*, whereof *b c d l m o p* show screw-heads in position to hold down iron rail, *R*, tight and firm upon the substructure of wood, *W*, which here is represented as one piece, instead of ties, to correspond with model. *a e n* show the position of screw-heads in fig. 5 when turned to liberate the rail when taking up the same.

Having mounted a common hand-car on rails laid, I affix to its projecting beam a common double-crank auger-borer, or other contrivance, into the socket of whose spindle, adjusted to bore at the desirable place, I insert the bit, fig. 1 or 2, and to lock I turn the key, fig. 3, inserted in a hole at a right angle to the socket, holding the shank of the bit so that a portion of the key at *n* will occupy the catch *n'* in the shank of the bit. To unlock, I turn the key half way round, so that the catch *n'* in the key will be occupied by the shank of the auger bit. Having locked the bit and gauged it by putting the key in *n'* or in *n''*, according to the depth I desire, I bore the hole, enlarging its mouth by the cutting edge, *e*, constructed on the pod of the bit, sufficiently to admit the shank, *k*, of the screw-fastener without splitting the tie, the smaller part of the hole being the same diameter as that of the core of screw part of the fastener, leaving the thread of the screw to be embeded in the solid wood when it is screwed down. On screwing in the fastener, as indicated, the inclination of the under side of its head being no less downward than that of the thread of the screw upward, it follows that the under surface of the head of the screw when turned down will of necessity be in position always to find its bearing upon the upper side of the flange of the rail, that bearing being necessitated by that inclination, since that inclination prevents approach of the under surface of the head toward the flange, unless it is in position to bear on the flange screwed down. To liberate and lift the rail from the tie, it is only necessary to reverse the screw less than one revolution so as to bring the line of truncation parallel with the line of the edge of the rail, as shown in *a e* and *n* in fig. 5.

The advantages of my invention are numerous, some of which I will indicate. By this mode I fasten the rail down tight and hold it there, the holding power of a single screw substantially of the size and weight of an ordinary railroad spike, or about half a pound, having been found by experiment, when turned into a live-timber tie, to be from five thousand to ten thousand pounds, as the wood was more or less dense. Ten fasteners, the ordinary number for one rail on five ties, would hold tight against any ordinary strain, no matter how great the speed of the train, how steep the grade, or how short the curve; and as the rail becomes indented into the tie, and the screw-fastener is turned down accordingly, the holding power of the fastener is only increased rather than diminished, as in case of the ordinary spike, its penetration being deeper with the screw in the wood. My mode of fastening musters out of service for other labor multitudes of employees incident to roads with the common spike to keep them in repair. There are no drawing out and driving in of hook-heads, and no splitting and lacerating of ties consequent thereto; none of breaking and remaking, and not half the rotting and replacing; no wearing and tearing by continual impinging of wheels and rails; no new cars and engines to be built, and no loss of lives and property to be paid for from casualties contingent upon keeping rails forever loose; while the first cost of laying tracks with my screw-fasteners is incomparably less than that of the hook-headers, counting in the number lost and destroyed consequent to their being withdrawn to repair. In short, my mode of fastening down the rails and chairs of railways will prevent the expenditure of millions of money for repairing and otherwise incident to the present mode of fastening with hook-headers, and will, when adopted, increase the value of two thousand millions of stock capital invested in the railway enterprise. I make the head beveling to correspond to the counter-bevel of the flange of the rail, the screw pointed, but not otherwise tapering, and of single thread, as best suited for its purpose; its thread cut, and not moulded, as more convenient for a model; the head round, with one truncation, as best suited for illustration; but I do not restrict or limit my invention to said bevel, the shape of screw, and kind of thread, shape of head, whether round, square, longer or shorter, oblong, regular or irregular, single-hooked or double-hooked, or otherwise, so long as the principle thereof is unchanged.

But what I claim as my invention in the mode of fastening down the rails and chairs of rails of railways, and for analogous purposes, and desire to secure by Letters Patent, is—

Such an inclination of the under surface of a screw-head, truncated in its relation to the gauge of the thread of the screw, as to necessitate a bearing of that surface upon the flange of the rail so as to make the rail tight when screwed down, and the rail released by a reverse operation of the screw, the truncation being tangential to the shank of the screw, in the manner and for the purpose herein described.

HORACE T. LOVE.
